(Cl. D57—1)

FIG. 1.

FIG. 2.

FIG. 3.

FIG. 4.

FIG. 5.

FIGURE 1 is a perspective view of a telescope showing our new design;

FIGURE 2 is a top plan view thereof;

FIGURE 3 is a fragmentary side elevational view thereof with parts broken away;

FIGURE 4 is a rear elevational view thereof; and

FIGURE 5 is a front elevational view thereof.

The base portion is shown broken away in FIGURE 3 for convenience of illustration and is completely omitted in FIGURES 4 and 5.

The dominant feature of our design resides in the portion shown in full lines.

We claim:

The ornamental design for a telescope, as shown and described.
